FIG. 1 is a front perspective view of a rocker switch cover showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The long dashed lines indicate contour and form part of the claimed design. The relatively light shade lines indicate contour and not surface decoration.

The dashed broken lines are for the purpose of illustrating portions of the rocker switch cover and form no part of the claimed design.
